*Primary Examiner—M. N. PandozziAttorney, Agent, or Firm—Goldstein & Associates[57]*CLAIM

The ornamental design for a combined beverage and snack holder, as shown and described.

DESCRIPTION

FIG. 1 is a front right perspective view of a combined beverage and snack holder showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line showing of a straw, snacks, and a hand is for illustrative purposes only and forms no part of the claimed design.
